ROTARY COMPRESSOR FOR GAS OR LIQUIDS WITH ROTOR ECCENTRICALLY MOUNTED IN CYLINDRICAL HOUSING

Karel Voznica, Brunn, Czechoslovakia

Application February 18, 1949, Serial No. 77,086
In Czechoslovakia February 21, 1948

4 Claims. (Cl. 230—152)

1

The object of the invention is a rotary compressor with a rotor eccentrically mounted in the cylinder housing and having sealing blades slideable in radial slits, these blades being pressed by centrifugal force on to the interior cylindrical surface of the cylinder during operation of the compressor.

The drawback of the known compressors of this kind consisted in insufficient sealing on the faces of the cylinder housing, considerable leaking being observed at these points resulting from warming up of the compressor and wear of the blades so that such a compressor could not be used for high pressures.

The invention aims to remove this drawback and consists in that there are provided sealing blades consisting of alternately arranged compact blades and divided half-blades separated by a wedge-shaped gap, these latter being pressed on the cylinder covers by the pressure of oil. The hydrostatic oil pressure produced by the centrifugal force during rotation of the rotor exerts an adequate force so that there is no unduly high friction on the surfaces of contact between the blades and the cylinder covers.

The efficiency of seal attained on the inner faces of the housing of the compressor makes it furthermore possible to use an improved system of distribution of the compressed medium which system consists in that a pair of longitudinal ducts are arranged in the rotor adjacent each blade, said ducts communicating one towards the suction cover and the other towards the delivery cover of the compressor while arcuate distribution ducts are arranged coaxially with the rotor in the cylinder covers. The distribution is attained by alignment of the lateral mouth of the rotor ducts with the corresponding arcuate ducts in the cylinder covers, thus making it possible to use, for filling or delivery, a larger portion of the rotor revolution than it was possible up to now and thus to improve the filling and emptying of the working space.

The object of the invention is illustrated by way of example on the attached drawing in which:

Fig. 1 is an axial longitudinal section of the compressor,

Fig. 2 a cross section taken on line II—II of Fig. 1, with illustration of the distribution at the suction end, and

Fig. 3 is a section taken on line III—III of Fig. 1, with illustration of the distribution at the delivery end of the cylinder.

On the base 1 is mounted the compressor body

2

comprising a vertical plate 2 fastened to the base by screws, and a casing 3. The vertical plate is connected to the casing by screws.

The vertical plate 2 and the casing 3 are penetrated centrally by a shaft 4 on which a rotor 5 is mounted. Eccentrically to the latter is situated a ring 6 forming the working cylinder the interior of which serves as a sliding surface for two groups of blades 17 and 17' which are not connected to each other and are radially slideable in radial slits 7 of the rotor 5.

To the faces of the rotor adhere the covers 8, 9 of the cylinder space which are connected with the vertical plate by screws 25, passing through circular holes of the ring 6.

In each of the front covers 8, 9 is situated centrally to the rotor one arc-shaped groove 10, 11 of which the groove 10 is, by means of a duct 12 passing through the cover 8 and the vertical plate 2, with a fitting 13 to which the suction tube of the compressor is connected while the second groove 11 by a duct 14 communicates with the space 15 between the cover 9 and casing 3, which space is the delivery space of the compressor and to which the delivery tube 16 is connected.

The loose blades 17, slideable in radial slits 7 and touching the covers 8 and 9, have the length of the cylinder and are exposed, each independently from the other blades of the same group, to centrifugal force when the rotor revolves. Between each two compact blades 17 are inserted two parted half-blades 17' enclosing between them a wedge-shaped gap 17''. During rotation of the rotor the gap is filled and the hydrostatic pressure produced by centrifugal force presses the blade halves 17' towards the covers 8 and 9. The lubricating oil is supplied from the oil reservoir which is formed by the delivery space 15 and which is filled by means of a lubricating pump.

Therefore the seal obtained by these blades is perfect even at high pressures.

The delivery space 15 is filled with oil to a certain level, the oil screen 18 preventing the oil from entering the delivery tube 16. The packing gland 19 prevents the escape of oil at the shaft end 4 and also the sucking of false air as well as escape of the medium at this point. Four ducts 20, 20', 21, 21' situated near the blades 17, 17' and provided in the rotor 5 cooperate with the arcuate grooves 10, 11 in the front covers 8, 9. Pairs of these ducts 20, 20' and 21, 21' are opposed to each other; the ducts 20, 20' cooperate with the arcuate groove 10 com-

municating with the suction tube and the ducts 21, 21' cooperate with the arcuate groove 11 communicating with the delivery space.

In Fig. 2 is illustrated in dotted lines the arcuate groove 10 in the cover 8 and distribution of the medium at the suction end takes place when the mouth of the duct 20 or 20' aligns with the groove 10 which is long enough to keep up the communication with the suction tube for the whole time of revolution of the rotor during which the space 22 increases its volume. The communication with the delivery groove 11 (dotted in Fig. 3) is realized when the mouth of the delivery duct 21 or 21' aligns with the groove and the length of this groove is selected so as to establish this communication at a moment when the pressure in the diminishing crescent-shaped working space reaches the working pressure of the compressor, and to keep it up for the whole time of diminution of the working space. Thus ideal filling and perfect emptying of the working space is obtained with small dead space and thereby also good efficiency of the compressor.

The shaft 4 is formed with a longitudinally extending bore 27 which communicates at one end thereof with the pressurized chamber 15. A plurality of radially extending passages 28 are formed in the shaft 4 and communicate at their opposite ends with the slits 7 and the bore 27. The lubricating passages 29 extend from the bore 27 for lubricating the shaft bearings. In operation, the fluid under pressure will pass through the bore 27 and passages 28 into the slits 7 and will fill the wedge-shaped space 17' between the blades 17'. The blades 17' will then be urged against the covers 8 and 9 for sealing the blades relative to the covers 8 and 9. The fluid passing into the slits 7 will also serve to lubricate the blades and decrease the wear thereof.

What I claim is:

1. A rotary compressor comprising a rotary cylinder eccentrically mounted in a cylindrical housing, said cylindrical housing being closed by flat covers at each end, an outer casing enclosing the cylindrical housing and defining a pressure fluid containing space between said casing and said housing, radial slits formed in said rotary cylinder and opening at the opposite ends of the latter, sealing blade assemblies radially slidable in said slits and composed by alternately arranged one piece blades and pairs of axially separable blade halves, each pair of blade halves defining a gap between their confronting edges, a central bore in said cylinder communicating at one end with said pressure fluid containing space, and radial ducts in the rotary cylinder connecting said central bore with the bottom of each of said radial slits so that fluid under pressure may pass from said pressure fluid containing space into said gaps to move the related blade halves axially into sealing engagement with said flat covers.

2. A rotary compressor comprising a rotary cylinder eccentrically mounted in a cylindrical housing, said cylindrical housing being closed at one end by a suction cover and at the other end by a

delivery cover, an outer casing enclosing said cylindrical housing and defining a pressure fluid containing space between said outer casing and said housing, radial slits formed in said rotary cylinder and opening at the opposite ends of the latter, sealing blade assemblies radially slidable in said radial slits and composed by alternately arranged one piece blades and pairs of axially separable blade halves, each pair of blade halves defining a gap between their confronting edges, a central bore in said rotary cylinder communicating at one end with said pressure fluid containing space, radial ducts in the rotary cylinder connecting said central bore with the bottom of each of said radial slits so that fluid under pressure may pass from said pressure fluid containing space into said gaps to move the related blade halves axially into sealing engagement with said flat covers, a pair of longitudinal ducts provided in said rotary cylinder in proximity of each of said blade assemblies, said longitudinal ducts opening radially outward at the periphery of said rotary cylinder and alternately at the ends of the latter facing said suction and delivery covers, arcuate grooves formed in said suction and delivery covers concentrically with the axis of rotation of said rotary cylinder to establish the inlet and outlet, respectively, of the fluid being compressed.

3. A rotary compressor according to claim 2, wherein said confronting edges of said pairs of blade halves diverge in the direction toward the axis of rotation of said rotary cylinder so that said gaps are substantially V-shaped.

4. A rotary compressor according to claim 2, including an outlet duct extending from said arcuate groove formed in said delivery cover and opening into said pressure fluid containing space, an outlet port formed in said outer casing for communication with a point of use, and an oil separator situated in said casing before said outlet port.
